DESIGN FOR A PLASTIC FILM TABLECLOTH

Robert P. Magid, Forest Hills, N. Y.

Application July 26, 1948, Serial No. 147,776

Term of patent 3½ years

(Cl. D92—26)

To all whom it may concern:

Be it known that I, Robert P. Magid, a citizen of the United States, residing at Forest Hills, in the county of Queens and State of New York, have invented a new, original, and ornamental Design for a Plastic Film Table Cloth, of which the following is a specification, reference being had to the accompanying drawing, forming a part thereof.

The figure is a plan view of a quarter section of a plastic film tablecloth, showing my new design. The other three quarter sections are identical therewith and arranged in proper relation to complete the plastic film tablecloth.

I claim:

The ornamental design for a plastic film tablecloth, substantially as shown and described.

ROBERT P. MAGID.
